UNITED STATES PATENT OFFICE.

PHILEMON O. DICKINSON, OF NEWARK, NEW JERSEY, ASSIGNOR TO UNGER BROTHERS, OF SAME PLACE.

DESIGN FOR A BACK FOR BRUSHES, &c.

SPECIFICATION forming part of Design No. 26,271, dated November 17, 1896.

Application filed October 10, 1896. Serial No. 608,525. Term of patent 3½ years.

To all whom it may concern:

Be it known that I, PHILEMON O. DICKINSON, a citizen of the United States, residing in Newark, in the county of Essex and State 5 of New Jersey, have invented and produced a new and original Design for Backs of Mirrors and Similar Articles, of which the following is a description, reference being had to the drawing accompanying and forming a 15 part of the same.

The outline shape of the back of the mirror is oval, as also that of the handle of the mirror, though the latter is appropriately smaller.

15 The motive of the design is a heavy, pronounced, and broadly-applied rococo arrangement of combined shell and scroll masses. Thus the upper part of the back of the mirror bears the pronounced rococo-work A, 20 which covers the upper end or about one-third of the entire back of the mirror. At the sides of the mirror are the broad band-like designs B and C, extending in breadth at least across a quarter of the surface of 25 the back. At the bottom portions of the back are two conventionalized rococo-shell figures D and E, which interspersed with filing embellishments cover practically the lower third of the surface of the back of the

brush. These various elements are disposed 30 to surround and produce the plain-surfaced shield-like figure F.

The design figures at the lower end of the back are continued onto the handle of the same, as shown at G, covering practically 35 the entire surface thereof except at the broadest portion, where the surface of the handle is left plain and the design surrounding the same effects the shield-like figure H, harmonizing with the shield figure F. The lower 40 end of the handle is entirely covered by the rococo-design mass I.

The essential features which characterize this design as a whole are broad and heavy 45 rococo shell and scroll masses practically covering the surfaces of the back and handle except the two bare or shield-like parts, one on the back and the other on the handle.

The essential features of design are those above set forth. 50

What is claimed as new is—

The design for the back of a mirror or similar article, substantially as shown and described.

PHILEMON O. DICKINSON.
